COOLING BED

Gustaf L. Fisk, New Fairfield, Conn., assignor to
Mesta Machine Company, West Homestead,
Pa., a corporation of Pennsylvania

Application September 29, 1941, Serial No. 412,801

6 Claims.

(Cl. 80—42)

This invention relates to cooling beds for a variety of products and, in particular, to cooling beds having provisions for the annealing of flat bars in a continuous pack.

Cooling beds having provisions for such pack annealing have been used for many years. Certain forms of such beds are shown in my Patent 1,761,470, Fisk et al. Patent 1,954,123 and Peterson Patent 1,834,728. The known cooling beds, however, have been required to anneal rolled bars of relatively narrow widths only, say up to 4". More recently, it has appeared desirable to subject much wider bars, e. g., up to 8" wide, to pack annealing, but this cannot be accomplished successfully by the structures and mechanisms known previously. In addition, when pack annealing bars on beds of known types, it is found that the bars do not readily separate from each other at the discharge end of the pack. Instead, the bars have a tendency to "shingle" so that considerable time and labor are required to separate them preparatory to subsequent handling.

I have invented a novel cooling bed which fully overcomes the aforementioned objections to such beds as previously known. In the preferred embodiment, I provide retreating abutments adapted to support a pack of flat bars on edge during cooling as they progressively move across the pack annealing section of a cooling bed. The retreating abutments depend from supports above the pack annealing section of the cooling bed, which supports are mounted for tilting movement to restore the abutments by gravity to the starting position or to adjust the elevation of the abutments for bars of different widths. The bars are delivered in position against the abutments and to the pack by rotatable packing arms similar to those shown in the prior patents mentioned above.

Means are provided for separating the leading bar from the remaining bars constituting the pack, in such manner as to avoid any "shingling" and to insure a prompt and positive separation.

For a complete understanding of the invention, reference is made to the accompanying drawings which will be described and explained in detail hereinafter. In the drawings,

Figure 1 is a typical transverse section through a cooling bed with parts in elevation, the showing being largely diagrammatic;

Figure 1A is a partial end elevation of the retreating abutment and its tilting support;

Figures 2 through 4 are diagrams illustrating the progressive steps in starting and building a pack of flat bars of small width for progressive cooling in contact with each other, as carried out by the apparatus of Figures 1 and 1A; and

Figure 5 is a view similar to Figure 4 showing the operation of forming a pack of bars of the maximum width.

Referring now in detail to the drawings and, for the present, to Figures 1 and 1A, hot-rolled bars 10 are received along one side of a cooling bed indicated generally at 11 on a run-in conveyer comprising a plurality of motor-driven rollers 12. Arms 13 are movable longitudinally of the rollers 12 to serve as a "kick-off" by displacing the bars 10 laterally from the rollers.

The cooling bed 11 comprises a sloping skid section 14, an arcuate skid section 15, a packing section 16, a sloping discharge section 17 and a final cooling section 18. The various sections of the bed are composed of skids formed from suitable metal bars supported in any convenient manner, for example, as disclosed in the prior patents above mentioned. The final cooling section 18 may conveniently take the form illustrated at 18 in Patent 1,954,123. The bars forming the packing section 16 with discharge section 17 and the arcuate skid section 15 are pivoted on a longitudinal shaft 19 whereby the packing section may be tilted to discharge bars delivered thereto immediately, in case pack annealing is not desired.

The shaft 19 is also provided with packing arms 20 disposed between adjacent bars of the sloping skid section 14 and the arcuate skid section 15. These arms serve to move a bar from a position at the foot of the sloping skid section 14 upwardly over the arcuate skid section 15 to the entering side of a pack of bars disposed on edge, indicated generally at 21. The bars are delivered to the sloping skid section 14, as previously indicated, by the laterally movable arms 13 which act as a "kick-off."

The novel pack supporting means which I have invented particularly for the purpose of maintaining a pack of extra wide bars as well as packs of bars of ordinary widths, is indicated generally at 22. It comprises a plurality of arms 23 spaced along the length of the cooling bed and pivoted on pins 24 in the main frame members of the bed supporting the conveyer rollers 12. Each arm 23 is provided with a transverse bar 25, extending through and welded or otherwise secured thereto. A sleeve 26 is slidable along each bar 25 and has a pack supporting abutment or finger 27 depending from the outer end thereof and a counterweight 28 formed adjacent the inner end thereof. As shown in Figure 1, the lower ends 50 of the abutments 27 are adapted to engage the upper edge of the leading bar in the pack 21 and thereby support the entire pack with the bars thereof on edge as they move successively across the pack annealing section 16 of the cooling bed. The diameter of the bar 25 is only a fraction of the inside diameter of the sleeve 26, whereby the former has contact with the latter throughout only a relatively small arc.

The arms 23 are rotatable on the pins 24 to restore the sleeves 26 and the pack supporting

abutments 27 to their initial position and to adjust the level of the lower end of the abutments collectively according to the width of the bars being handled as well as individually for alignment. The collective movement of the arms 23 is effected by rotation of a shaft 29 journaled in the main frame members of the bed, having cranks 30 spaced therealong and links 31 pivoted to the cranks 30 and the arms 23. Each link 31 includes a bar 32 having a sleeve 33 formed at the end thereof and a rod 34 having a clevis at the upper end by which it is pivoted to the arm 23. The lower end of the rod 34 passes through the sleeve 33 on the bar 32 and is threaded to receive nuts 35. A compression spring 36 is disposed on the rod 34 between the clevis end thereof and the sleeve 33. By suitable adjustment of the nuts 35, the spring 36 may be placed under the desired initial compression. When so adjusted, the link 31 serves to transmit positively any force applied thereto less than that necessary to further compress the spring.

A striker plate 37 is slidably mounted on bolts 38 extending through the upper end of the arm 23. A compression spring 39 surrounding the bar 25 bears on the striker plate 37 and the end of the arm 23. This provides a cushioning of the blow which is struck by the sleeve 26 on tilting of the bar 25 to restore the abutment 27 to the starting position or on tilting the bar 25 to a substantially vertical position to clear the bed. The springs 36 and 39 are so dimensioned that the latter will absorb all the impact of the sleeve 26 sliding down the bar 25. Lugs 40 on the striker plate 37 spaced radially outward from the bar 25 hold the end of the sleeve 26 against the bar when the sleeve engages the plate.

Any convenient drive may be provided for the shaft 29, e. g., a suitable motor and a gear reducer, whereby all the arms 23 along the full length of the cooling bed may be simultaneously operated either for adjustment to suit the width of the bar 10 or for setting the pack supporting abutments to starting position.

Referring now to Figures 2 through 4, the manner in which the apparatus described above effects the starting and building of a pack of narrow bars, say 2" wide, for progressive cooling in contact with each other will now be explained. The shaft 29 is first operated so as to swing the arms 23 to raise the bars 25 to a position where the sleeves 26 with abutments 27 will slide to starting position. After this telescoping movement, the shaft 29 is reversed to lower the bottom of the abutments 27 to a level such as illustrated in Figure 2 preparatory to forming a pack of relatively narrow bars 10. The initial or starting position of the abutments 27 is indicated in dotted lines in Figure 2. The first bar is received by the conveyer rollers 12 and is kicked off by the arms 13 to slide down the sloping skid section 14 of the bed. When the bar reaches the bottom of the sloping skid section, the shaft 19 is operated to swing the packing arms 20 to the position indicated in Figure 2. The outer ends of the packing arms engage the pack supporting abutments and displace them to the solid line position, simultaneously delivering the bar 10 with its upper edge against the abutments. The bars forming the pack annealing section 16 of the bed have a small shoulder 41 formed therein adapted to engage the lower edge of the bars as delivered by the arms 20 from the arcuate skid section 15. When the bar 10 has been positioned as described, it will thus be firmly supported on edge after

retraction of the packing arms 20. Repeated operation of the packing arms to deliver additional bars causes no further displacement of the abutments 27, until the pack has reached the size illustrated in Figure 3. From then on the abutments are forced to retreat as bars are added to the pack. The movement of the abutments is resisted by the friction between the contacting surfaces of the sleeves 26 and bars 25. This is easily overcome by the force exerted by the arms 20, but is sufficient to support the bars of the pack on edge during the building of the pack and after it has been completed. It will be understood that after the placing of the first few bars of relatively small width in the pack, displacement of the abutments 27 is effected by the addition of successive bars to the entering side of the pack and the displacement thereby of the previously delivered bars.

The procedure described above continues until a full pack 21 has been built up on the pack annealing section 16, as illustrated in Figure 4 and Figure 1. With a full pack as there shown, it will be evident that the addition of another bar will cause the first bar delivered to pass beyond the pack annealing section of the bed whereupon it is free to fall down the relatively steeply inclined skids forming the sloping section 17 of the bed. This arrangement insures a clean separation of each bar individually from the remaining bars of the pack. This results from the fact that the weight of the bar is much greater than the frictional force exerted thereon by the abutments 27, which is the only force restraining the bar against falling.

Continued operation through the above described cycle causes the discharge of the leading bar from the delivery end of the pack each time an additional bar is delivered to the entry side of the pack. When the desired amount of bars has been rolled and delivered to the pack annealing section, the last bars rolled, sufficient in number to form a full "residual" pack, are left on the pack annealing section 16 until they have been fully annealed by slow cooling. The entire pack annealing section of the bed is then tilted to cause the bars forming the residual pack to slide downwardly onto the final cooling or carry-over bed 18.

The manner in which the apparatus shown in Figures 1 and 1A operates to start, build and maintain a pack of bars of maximum width, e. g. 8", is illustrated in Figure 5. The shaft 29 is first operated to cause the sleeves 26 and the abutments 27 to slide downwardly on the bars 25 until the sleeves engage the striker plates 37. The shaft 29 is then reversed to position the bars 25 so that when the abutments 27 have been retracted to the solid line position of Figure 5, the lower ends thereof will be only slightly below the upper edges of the bars 10'. In other words, whereas the transverse bars 25 are substantially horizontal when handling narrow bars on the pack annealing section, they are at a slight angle to the horizontal when handling the wider bars.

Before the first bar 10' is delivered to the pack annealing section, the packing arms 20 are operated through a complete cycle. The engagement of their outer ends with the abutments 27 causes the latter to move from the dotted line position to the shaded line position shown in Figure 5. The first bar 10' is then kicked off from the conveyer rolls and delivered by the packing arms. This step displaces the abutments 27 from the shaded line position to the chain line position. The shoulder 41 serves in the manner pre-

viously explained to sustain the bars delivered to the pack annealing section upon retraction of the packing arms. By the delivery of additional bars in the same manner, the full width of the pack is built up and the abutments 27 are pushed back to the solid line position shown in Figure 5. It will be apparent that since the abutments are pushed uphill with the aforementioned adjustments to accommodate them to bars of the maximum width, the resisting force is greater. This is desirable since the wider bars are heavier and require a greater restraining force to support them on edge.

When the full pack has been built, the leading bar falls down the sloping skid section in the same manner as previously described with the addition of the next bar to the entering side of the pack.

Several of the advantages of my invention have been mentioned above in the course of the detailed description. As already stated, the invention provides an improved cooling bed having simple and relatively inexpensive provisions for the pack annealing of bars of various widths up to a maximum of approximately 8" or the maximum the cooling bed as a whole is suited to handle. In this respect, the invention is a marked improvement over prior pack annealing cooling beds since the pack supporting members of the latter would have to be made large and cumbersome to accommodate bars of a width as great as 8", and would unduly increase the width and the cost of the cooling bed as a whole. In addition, the leading bar of the pack separates itself quickly and cleanly from the remainder of the pack as a succeeding bar is delivered to the entry side thereof.

The width of the pack annealing section of the bed may be chosen as the theoretical minimum required in view of the maximum width of the bars to be annealed, the length of the cooling bed and the rolling speed of the mill delivering bars to the bed. This is not the case with existing beds above referred to, which are partially ineffective due to "shingling" on the pack annealing section. Regardless of the width of the pack annealing section, the invention provides means for laterally supporting rolled bars of various widths on edge as they progress through the packs from the entering side to the discharge side thereof.

By using tubes for mounting the pack engaging abutments, I provide for circulation of air to prevent excessive heating of the pack supporting means and a structure which is relatively cheap to manufacture. The pack engaging abutments are located in the same transverse planes as the packing arms 20. This avoids any bending or marking of the hot bars which might result if the force exerted by the packing arms were not exactly in line with the restraining force exerted by the friction between the abutments and their supports. It may not be necessary, however, to provide a pack engaging abutment for every packing arm.

The construction of the links 31 is such as to permit individual adjustment of the transverse bars 25, by turning nuts 35, to aline all the pack engaging abutments 27 throughout the length of the bed to insure simultaneous engagement thereof by the bars delivered to the pack annealing section.

Although I have illustrated and described but a preferred embodiment of the invention, it will be recognized that changes in the construction and arrangement may be made without depart-

ing from the spirit of the invention or the scope of the appended claims.

I claim:

- 5 1. In a cooling bed comprising a run-in conveyor and a section to accommodate a pack of thin flat bars which do not stand on edge without lateral support, for pack-annealing, means for affording lateral support to bars delivered on edge to said section, means spaced along the length of and over-hanging said conveyor for supporting said means, and common means for adjusting all said second-mentioned means whereby to position said first-mentioned means at a pre-determined elevation.
- 15 2. In a cooling bed comprising a run-in conveyor and a section to accommodate a pack of thin flat bars which do not stand on edge without lateral support, for pack-annealing, means for affording lateral support to bars delivered on edge to said section in a forward-leaning position relative to the direction of movement, while maintaining the leading bar free to fall away as it reaches the discharge side of said section, and a shoulder at the entering side of said section adapted to retain the lower edge of the last bar delivered and cooperate with said means in starting, building and maintaining a pack of bars on said section.
- 20 3. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said cooling bed at a substantial height above said section and fingers depending from said arms and at a substantial angle thereto for supporting the bars, said fingers being slidable along said arms upon engagement by the leading bar of a pack on said section.
- 25 4. A cooling bed as defined in claim 3 characterized by said over-hanging arms being movable to cause shifting of the fingers by gravity to pack starting positions.
- 30 5. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said cooling bed at a substantial height above said section and fingers depending from said arms and at a substantial angle thereto for supporting the bars, said fingers being slidable along said arms upon engagement by the leading bar of a pack on said section and said over-hanging arms being adjustable to vary their inclination and thereby vary the support afforded by said fingers.
- 35 6. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.
- 40 7. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.
- 45 8. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.
- 50 9. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.
- 55 10. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.
- 60 11. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.
- 65 12. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.
- 70 13. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.
- 75 14. In a cooling bed comprising a run-in conveyor and a section to accommodate a pack of thin flat bars which do not stand on edge without lateral support, for pack-annealing, means for affording lateral support to bars delivered on edge to said section including arms spaced along and over-hanging said conveyor and at a substantial height above said section, fingers depending from said arms at a substantial angle thereto for supporting the bars, and mounting means for said fingers movable along said arms whereby said fingers may be positioned adjacent the entering side of said section for starting a pack and progressively moved to the exit side of said section for supporting a completed pack.

GUSTAF L. FISK.
